United States Patent

Des. 242,554

Patented Nov. 30, 1976

242,554

DEVICE FOR USE IN THE PRACTICE OF THE OCCULT ARTS

Gillis P. Flanagan, Glendale, Calif., assignor to Laser Sound Systems, Inc., Glendale, Calif.

Filed Oct. 9, 1974, Ser. No. 513,482

Term of patent 14 years

Int. Cl. D11—02

U.S. Cl. D31—24

FIG. 1 is a perspective view of a device for use in the practice of the occult arts showing my new design;

FIG. 2 is an end elevational view; and

FIG. 3 is a plan view of the side opposite that shown in FIG. 1.

I claim:

The ornamental design for a device for use in the practice of the occult arts, as shown and described.
